UNITED STATES PATENT OFFICE.

OTTO P. RINDELHARDT, OF LONDON, ONTARIO, CANADA.

APPARATUS FOR CARBONATING BEER, ALE, AND THE LIKE.

1,215,864.

Specification of Letters Patent.

Patented Feb. 13, 1917.

Application filed October 15, 1913. Serial No. 795,255.

To all whom it may concern:

Be it known that I, OTTO P. RINDELHARDT, a citizen of the United States, and resident of the city of London, in the county of Middlesex and Province of Ontario, Dominion of Canada, have invented a new and useful Apparatus for Carbonating Beer, Ale, and the like; and I hereby declare that the following is a full, clear, and exact description 10 of the same.

The object of my present invention is to utilize the carbonic acid gas generated in the fermenting tun or tuns for recharging the finished liquid in the storage cask or casks 15 by taking the carbonic acid gas as it is generated, discharging it direct into the finished liquid, and utilizing the pressure of the carbonic acid gas in the fermenting tun to force it through the said liquid, suitable 20 means being provided for distributing the volume of carbonic acid gas into minute sprays, as it passes into the liquid.

In carrying out my invention the carbonic acid gas is conveyed direct from the fermenting liquid in the fermenting tun to the finished liquid in the storage cask, the pressure of the carbonic acid gas during the fermentation being utilized for forcing it from 25 its place of origin to its place of use, the storage cask containing the finished liquid being provided with means for dividing the carbonic acid gas into minute sprays to facilitate its impregnation of the liquid as 30 hereinafter set forth and particularly 35 pointed out in the claim.

In the drawings Figure 1, is a broken elevation of the apparatus showing the manner in which the carbonic acid gas is conveyed from the fermenting tun or tuns to 40 the finished liquid in the storage cask or casks.

Fig. 2, is an enlarged detail view of one of the distributers of the carbonic acid gas.

Like characters of reference refer to like 45 parts throughout the specification and drawings.

The fermentation of the worts takes place in a closed fermenting tun *a* and the carbonic acid gas as it is liberated during the 50 fermentation rises to the top of the worts and accumulates below its cover *b*.

As shown in Fig. 1 of the drawings the cover *b* is provided with an outlet pipe *c* fitted with a safety valve *d* and with a valve 55 controlled pipe *e* leading to the closed storage cask *f*. As shown in Fig. 1 of the draw-

ings the pipe *e* leads into the bottom of the storage cask *f* and, within it, is provided with a distributor *g*. This distributor consists of a metallic ring *h*, having a hollow pipe connection *i* coupled to the adjacent end of the pipe *e*, and formed preferably with two or more passages or bores *j* leading from the hollow pipe connection, through which the carbonic acid gas can 60 flow to the interior of the metallic ring *h*. Bolted to each side of the metallic ring *h* are clamping rings *k*, *k'*, and between the clamping rings *k*, *k'* and the metallic ring *h* are permeable covers *l*, *l'*, said permeable covers being securely fastened to the metallic ring *h* by the clamping rings and forming with the metallic ring a distributing chamber *m* into which the carbonic acid gas is discharged through the passages *j* 70 from the pipe *e*.

The pressure of the carbonic acid gas in the fermenting tun forces it through the outlet pipe *c*, the pipe *e*, the pipe connection *i*, and passages *j*, into the distributing chamber *m*, and from the distributing chamber *m* through the pores of the permeable covers *l*, *l'* into the liquid contained within the storage cask *f* to carbonate it.

The fermenting tun may be connected 85 with any desired number of storage casks, and the carbonic acid gas as it is liberated may be conveyed simultaneously to all the storage casks by a suitable pipe line *r*, the number of casks depending upon the capacity of the fermenting tun; any desired 90 number of fermenting tuns may be coupled together and connected to the pipe line *r*; and the storage casks may be provided with outlets *o*, preferably connected together by 95 a discharge pipe *p* having a gage *q* indicating the pressure in the discharge pipe.

The terms "fermenting tun" and "storage casks" have been used throughout the foregoing description and these terms are intended to include within their meaning, any vessels suitable for use in connection with the brewing or storing of the liquid which will permit of the carbonic acid gas being collected from the fermenting liquid and forced through the finished liquid to carbonate it.

Having now particularly described the nature of my said invention and in what manner the same is to be performed, I declare that what I claim is:—

In an apparatus for carbonating beer, ale,

and the like, a distributor comprising an annular ring, a hollow pipe connection therefor, said ring having passages leading from the bore of the hollow pipe connection to the bore of the ring, clamping members removably secured to the side faces of said ring, and permeable covers contained between the side faces of the ring and the clamping members and forming therewith

a distributing chamber into which the carbonic acid gas is discharged through said passages from the bore of the hollow pipe connection. 10

Toronto September 27th 1913.

OTTO P. RINDELHARDT.

Signed in the presence of—

CHAS. H. RICHES,
I. GRAHAM BOYD.
